UNITED STATES PATENT OFFICE

168,399

TROLLING DEVICE

Olga D. Harris, New Orleans, La.

Application May 20, 1952, Serial No. 19,798

Term of patent 14 years

(Cl. D31—4)

To all whom it may concern:

Be it known that I, Olga D. Harris, a citizen of the United States, residing at New Orleans, State of Louisiana, have invented a new, original, and ornamental Design for a Trolling Device, of which the following is a specification, reference being had to the accompanying drawing, forming a part thereof.

Figure 1 is a view in side elevation of a trolling device, showing my new design.

Figure 2 is a top plan view.

Figure 3 is a bottom plan view.

Figure 4 is an elevated front view.

I claim:

The ornamental design for a trolling device, as shown.

OLGA D. HARRIS.
